CLAIM

The ornamental design for a valve actuator, as shown and described.

DESCRIPTION

FIG. 1 is a top perspective view of a valve actuator according to the disclosure.

FIG. 2 is a front view of the valve actuator of FIG. 1.

FIG. 3 is a rear view of the valve actuator of FIG. 1.

FIG. 4 is a side view of the valve actuator of FIG. 1.

FIG. 5 is another side view of the valve actuator of FIG. 1.

FIG. 6 is a top view of the valve actuator of FIG. 1; and, FIG. 7 is a bottom view of the valve actuator of FIG. 1.

The broken lines shown in the figures are for the purpose of illustrating portions of the valve actuator and form no part of the claimed design.
